UNITED STATES PATENT OFFICE.

JOSEPH WAGNER, OF NEW YORK, N. Y.

GLASS-CUTTING MACHINE.

1,183,144.

Specification of Letters Patent. Patented May 16, 1916.

Application filed January 27, 1915. Serial No. 4,785.

To all whom it may concern:

Be it known that I, JOSEPH WAGNER, a citizen of the United States of America, residing in the borough of Queens, in the city of New York, county of Queens, and State of New York, have invented certain new and useful Improvements in Glass-Cutting Machines, of which the following is a specification, reference being had to the accompanying drawings.

My invention relates to improvements in glass-cutting machines; and an object of this invention is to provide a glass-cutting machine which will be simple in construction, comparatively cheap in manufacture and efficient in operation and use.

Another object of this invention is to provide a glass-cutting machine which will be suitable for cutting glass into either circular shapes or oval shapes.

In the drawings illustrating the principle of this invention and the best mode now known to me of applying that principle, Figure 1 is a section on the line I—I of Fig. 2; Fig. 2 is an end view looking in the direction of the arrow A of Fig. 1; Fig. 3 is a section on the line III—III of Fig. 1; and Fig. 4 is a detail showing one of the crank-arms in perspective.

To the work-bench *a* there is screwed an inverted L-shaped bracket support *b* into one end of the horizontal arm *c* of which there is screwed the lower end of a post *d* the upper end *d'* of which is reduced and carries a ball-shaped member *d''*. The other end of the horizontal arm *c* is formed with a slot or opening *c'*; and above this opening there rests on the arm *c* a slide *e* which is held in place by gibbs *f*, *f'* which are fastened to the arm *c* by means of screws *g*. The slide *e* is kept in line and held from rattling between the gibbs *f*, *f'* by means of screws *g'*. This slide *e* carries a tubular shaft-bearing *h* which extends downwardly through the slot *c'* and in which there is rotatably-mounted a vertical cutter-shaft *i*. To the upper end of the latter there is fastened a laterally-extending arm *j* which passes through an eye *k'* formed in one end of a crank-arm *k* fast upon the lower end of a vertical operating shaft *m* to the upper end of which there is secured a crank-arm *n* provided with a knob or handle *o*. Upon the operating shaft *m* there is mounted a ball-shaped member *d**, which is similar in

all respects to the ball-shaped member *d''*; and these ball-shaped members *d''*, *d** are connected by means of an arm *p* which is bifurcated at both of its ends *p**, *p''*. The bifurcated end *p** is pivotally fastened by means of screws *q** to the ball-shaped member *d**, while the other bifurcated end *p''* is similarly fastened by screws *q''* to the ball-shaped member *d''*. As is best shown in Figs. 2 and 3, the ball-shaped members *d''*, *d** are formed with flattened sides *r*. The arm *j* is held in the arm *k* by means of a thumb-screw *j'*. Between the arm *j* and the slide *e* there is interposed a helical spring *s* which is wound around the upper end of the vertical cutter-shaft *i* and serves to restore that shaft to its initial position, when the arm *n* is relieved from downward pressure. Upon the lower end of the vertical shaft *i* there is mounted a crank-arm *k''* which is similar to the crank-arm *k* herein-before referred to; and through an eye *k'* in this crank-arm *k''* there passes an arm *t* in one end *t'* of which there is mounted a diamond-holder *u* the lower end of which carries the glass-cutting diamond *v*. The arm *t* is held in its adjusted position in the arm *k''* by means of a thumb-screw *j''*.

The operation of my new glass-cutting machine will be readily understood from the foregoing and may be briefly described as follows: In order to cut circular shapes, the thumb-screw *j'* is loosened and the vertical shaft *i* and the slide *e* are moved until the axes of the vertical shafts *m*, *i*, lie in prolongation of each other. To determine the size of the circular shape, the thumb-screw *j''* is loosened and the arm *t* is moved laterally in the eye *k'*. After the adjustments have been made, the thumb-screws *j'*, *j''* are tightened. The operator then seizes the knob or handle *o* and presses downwardly against the tension of the coil-spring *s*, until the glass-cutting diamond *v* is brought against the face of the piece of glass resting on the work-table *a*; whereupon the operator swings the arm *n* and thereby turns the vertical shafts *m*, *i*, whereby the diamond *v* is made to trace a circle upon the glass lying on the work-table *a*. After the glass has been cut, the operator relieves the arm *n* from the pressure exerted through the knob *o* and the parts are restored to their initial position by the tension of the coil-spring *s*. When it is desired to cut an oval

shape, the vertical shaft *i* is moved until its axis no longer lies in prolongation with the axis of the vertical shaft *m*, whereupon the shape cut by the moving glass-cutting diamond *v* will be oval-like.

I claim:

1. A glass-cutting machine including a support; a cutter-shaft; a glass-cutting device fastened thereto; an operating shaft; a laterally-extending arm carried by the first-named shaft and fastened to the last-named shaft; and a downwardly swinging arm which is pivotally fastened to said support and carries the last-named shaft.
- 10 2. A glass-cutting machine including a support; a slide mounted on said support; a shaft-bearing carried by said slide; a cutter-shaft rotatably mounted in said shaft-bearing; a glass-cutting device carried by said shaft; a rotary operating shaft; and mechanism connecting said shafts.
- 15 3. A glass-cutting machine comprising a support; a shaft-bearing slidably mounted thereon; a rotary cutter-shaft mounted in said shaft-bearing; a glass-cutting device mounted on said cutter-shaft; a swinging arm fastened to said support; a spring for restoring said cutter-shaft to its normal position; an operating shaft mounted in said swinging arm; and mechanism for connecting said shafts.
- 20 4. A glass-cutting machine comprising a support; a shaft-bearing slidably mounted thereon; a rotary cutter-shaft mounted in said shaft-bearing; a glass-cutting device mounted on said cutter-shaft; a rotary operating shaft; and mechanism connecting said shafts, said mechanism connecting said shafts and permitting the same to be moved

out of and into axial alinement with each other.

5. A glass-cutting machine comprising a support; a shaft-bearing slidably mounted thereon; a rotary cutter-shaft mounted in said shaft-bearing; a glass-cutting device mounted on said cutter-shaft; a swinging arm pivotally fastened to said support; an operating shaft carried by said swinging arm; and mechanism connecting the shafts and permitting the same to be moved out of and into axial alinement with each other.

6. A glass-cutting machine comprising a support; a pair of shafts movable with respect to each other and into and out of axial alinement; a downwardly swinging arm which connects one of said shafts to said support, the other of said shafts being mounted therein; and a glass-cutting device carried by the other of said shafts.

7. A glass-cutting machine comprising a support; a pair of shafts movable with respect to each other and into and out of axial alinement; a downwardly swinging arm which connects one of said shafts to said support, the other of said shafts being mounted therein; a glass-cutting device carried by the other of said shafts; and mechanism for restoring said shafts to their initial position.

Signed at the borough of Manhattan, New York City, N. Y., this twenty-third day of January, A. D., 1915, in the presence of the two undersigned witnesses.

JOESPH WAGNER.
